United States Patent Office

Des. 214,282
Patented May 27, 1969

214,282

TIMING DEVICE OR SIMILAR ARTICLE

Raoul E. Rodriguez, Chicago, Ill., assignor to International Register Company, Chicago, Ill., a corporation of Illinois

Filed Aug. 19, 1968, Ser. No. 13,187

Term of patent 14 years

Int. Cl. D10—05

U.S. Cl. D42—7

FIG. 1 is a top plan view of a timing device or similar article, showing my new design;

FIG. 2 is a left side elevational view;

FIG. 3 is a face view taken along line 3—3 of FIG. 2;

FIG. 4 is a right side elevational view;

FIG. 5 is a rear elevational view; and

FIG. 6 is a front and bottom view taken along line 6—6 of FIG. 4.

I claim:

The ornamental design for a timing device or similar article, substantially as shown and described.
